UNITED STATES PATENT OFFICE.

GEORGE EDWARD PRENTICE, OF BERLIN, CONNECTICUT.

INTERLOCKING FASTENER.

Application filed April 20, 1925. Serial No. 24,472.

To all whom it may concern:

Be it known that I, GEORGE EDWARD PRENTICE, a citizen of the United States, residing at Berlin, in the county of Hartford and State of Connecticut, have invented certain new and useful Improvements in Interlocking Fasteners, of which the following is a specification.

My invention relates to improvements in interlocking fasteners of the kind in which a series of mating locking members are arranged along the opposed edges of a pair of strips of fabric or the like that constitute the border walls of an opening or gap in a garment, shoe, receptacle, or other article and that are adapted to be operated for being brought to the locking position or for being disengaged by means of a slide that is mounted thereon for longitudinal movement, and the object of my improvement is to produce an interlocking fastener structure in which the active interlocking elements are in the form of separate structures that are individually mounted along the fabric edges, are of simple form, economical in manufacture, and convenient and efficient in use.

In the accompanying drawing:

Figure 1 is a front elevation of a set of interlocking fasteners embodying my invention, arranged along the opposed edges of a pair of strips of fabric, and a slide.

Figure 2 is a similar view on an enlarged scale and with the front plate of the slide removed.

Figure 3 is a sectional view of the slide shown in Fig. 1.

Figure 4 is an end view of the slide.

Figure 5 is a plan view of the blank for the slide.

Figure 6 is a plan view of a blank for one of the interlocking members previous to swaging the yoke portion.

Figure 7 is a similar view of the same after swaging.

Figure 8 is an end view of the same, after being bent so as to receive the fabric edge.

Figure 9 is a fragmentary view on a further enlarged scale and in section showing a pair of interengaged elements and adjacent parts.

Figure 10 is a front elevation corresponding to Fig. 1 showing a modification of the interlocking fasteners.

Figure 11 is a sectional view on the line 11—11 of Fig. 10.

Figure 12 is a plan view of the blank for one of the fasteners shown in Figs. 10 and 11.

Figure 13 is an edge view of the same.

Figure 14 is a plan view of the blank for another modification of the interlocking fasteners.

Figure 15 is a top view of the same bent into U-shape previous to applying to the stringer or braid.

Figure 16 is a sectional view on the line 16—16 of Fig. 14.

Figure 17 is a longitudinal sectional view of a few of the fasteners of the form that is shown in Figs. 10 to 13 inclusive and on an enlarged scale, the fabric structure being shown generally diagrammatically, and showing in particular the overhang of the corners of the individual yokes of the fastener elements relatively to the edges of the wings.

My improved interlocking fastener comprises a set of interlocking fastener members 10 that, as shown, are distributed along the opposed edges 11 of a pair of strips 12 of braid, the structures of said edges 11 being relatively enlarged by incorporating therein a cord 13.

A slide 15, mounted for longitudinal movement on said members 10 serves to bring the mating members into engagement when moved upwardly, as in Fig. 1, and the reverse movement effects disengagement thereon.

The slide 15 is made of sheet metal and comprises a front plate 16 and a rear plate 17 that are positioned in spaced relation and are interconnected by means of an integral neck 18 in the form of a return bend at the upper end. Flanges 19 at the lateral edges of said plates serve as guides for the interlocking members 10 for movement in one direction, the opposed flanges being separated by an opening or slit 20 to admit the braid 12. For movement in the reverse direction guide walls 21 are provided that are located generally at the upper interior portions of the plates and that are formed by swaging the material at or adjacent the junctions of the body portions of the plates 16 and 17 and the neck 18. Said neck 18

comprises the return bend portion 22 at the upper end and a pair of opposed downwardly directed arms 23 that merge with the inner guide walls 21 and, by reason of 110

the swaging mentioned may be in face to face contact.

5 A handle may be provided for the slide 15 and may conveniently be applied to the neck structure 18.

The slide 15 has at the lower end a mouth 24 that is an operative fit for the mating interlocking members 10 in the engaged position, the lateral walls of said mouth 24 being defined by the lower straight and parallel portions 25 of the lateral flange walls 19.

10 At the upper end of the slide 15 are a pair of outlets 26, positioned in laterally spaced relation, for the exit of the two series 15 of interlocking members 10 individually, and said outlets 26 are defined on the upper inner sides by the swaged walls 21 mentioned. Said walls 21 converge downwardly and inwardly and meet at the apex 27 which 20 is at the axial line.

25 The outer boundaries of the outlets 26 are defined by the inclined converging portions 28 of the edge flange walls 19, said portions 28 meeting individually at an obtuse angle 25 the parallel wall portions 25, the vertices 29 thereof being located appreciably below the vertex 27.

30 Reverting to the interlocking members 10, shown in Figures 1-9 inclusive, these are formed of sheet metal; of symmetrical form; the blank being swaged at the middle portion and at the edges which correspond to the longitudinal ends in use; are bent into U-shape to provide spaced clamping arms; 35 are slipped over the edge portion of the braid, and finally; said arms are forcibly engaged with the fabric.

35 The arms 30 mentioned generally embrace the enlarged cord portion 13 of the fabric edge and the free ends thereof are provided with inwardly directed end portions 31 of hook-like form that are separated by a narrower slit-like space that more closely fits against the braid 12. The structure described permits securing the interlocking members 10 to the braid with a minimum of distortion or deformation, and also provides for a firm connection with the parts snugly fitting one with the other.

50 Considering the details of the interlocking elements proper, these comprise as to outward appearance a pair of projections 32, one at each longitudinal end that project beyond the adjacent end face 33 and are formed by swaging the edges or ends of the yoke portion 34 that connects the two clamping arms 30. The projections 32 are hook-like structures; are similar for the two ends; are similar, also, for the units on the two sides or braid strips; and interengage to effect the locking. In the engaged position, however, the hooks 32 enter within the space back of the adjacent yoke 34 and are substantially concealed. Also, as a detail, in 60 the engaged position the outer face of the

yoke 34 fits against the edge 11 of the braid 12.

I prefer to have the contour or edge portion 35 of the hook 32 of rounded or substantially semi-circular form and to provide 70 on the inner face of the adjacent portion of the yoke 34 a seat 36 of similar form, whereby the hook 32 of one unit will seat itself within the seat 36 of the cooperating unit. The structure defined provides for flexibility 75 under conditions of use.

Considering the structure as a whole, the parts described are adapted to be constructed and arranged so as to effect a substantially tight closure for a gap or the 80 like.

In carrying out the invention disclosed departures from the specific form of structure shown and described above may be made, having in mind particularly the details of 85 the interlocking fasteners, and some of the modifications shown will be briefly described.

90 In the form that is shown in Figs. 10 to 13 inclusive the interlocking fastener units 10^a are made from a substantially flat blank, without swaging the material at the yoke 34^a or anywhere else, and making said blank from material of appreciable thickness. The wings or clamping arms 30^a are wedge-shape, 95 having converging border edges 40. In use, the parts of said edges 40 that cooperate with the mating units 10^a are adjacent the corners 41 at the junctions of the wings 30^a and the yoke portion. 100

105 The corner 41 is defined in part by the outer face 42 of the yoke 34^a. By reason of using material of appreciable thickness, particularly as to the yoke 34^a, there is a corner 43 that is defined by the inner face 44 of the yoke 34^a and extreme edge face 45 of said material. Said inner corner 43 extends beyond or overhangs slightly though appreciably the lateral edge 40 of the adjacent wing 30^a. 110

115 Thus with adjacent lateral edges 40 in abutment the inner corners 43 enter within the space 46 between the wings 30^a and operate as holding or locking means to effect what may be described as front and back engagement of the units 10^a.

120 In the form that is shown in Figs. 14, 15, and 16 a flat blank is used and the front and back engagement is effected by means of a special formation of the top and bottom edges of the yoke portion 34^b of the units 10^b, whereby relatively more pronounced interengaging elements are provided. As shown, the bottom edge is provided with a downwardly directed V-shaped projection 50 and the top edge is provided with a correspondingly shaped recess or depression 51. 125

130 In all of the forms shown and described a substantially tight closure of the gap is effected and the holding effect against open-

ing of the gap involves engagement of parts of extensions at the top and bottom edges of that cooperate generally after the manner said part.

- 5 2. In a fastener construction as described 35 in claim 1, the face of the material of said hook and the adjacent portion of said part that is opposed to said portion of the inside face being inclined so as to fit the corresponding face of a mating unit. 40
- 10 3. In a fastener construction, opposed edge portions of fabric, fastener units mounted thereon in staggered relation, said units being individually of U-shape, comprising 45 a part that is opposed to and in face to a face contact with a portion of one of said edge portions, and having arms that are extended from said part and embrace said edge portion, and means on the top and bottom edges of said part, similar one to the other, provided on each of said units for 50 cooperating with a mating unit as fastener means.

15 I claim as my invention:—

1. In a fastener construction, opposed edge 55 portions of fabric, fastener units mounted 25 thereon in staggered relation, hooks on said units for engaging with mating units, said hooks being located one at each edge at the end of each of said units, said units comprising each a part that is opposed to a portion of the inside face of one of said edge 60 portions and that is in face to face contact therewith, and said hooks being in the form

GEORGE EDWARD PRENTICE.
